UNITED STATES PATENT OFFICE.

WINCENT KWASIS, OF NEWARK, NEW JERSEY.

LABEL-AFFIXING APPARATUS.

1,351,107.

Specification of Letters Patent. Patented Aug. 31, 1920.

Application filed May 1, 1919. Serial No. 293,958.

To all whom it may concern:

Be it known that I, WINCENT KWASIS, a citizen of Russia, residing at Newark, county of Essex and State of New Jersey, have invented certain new and useful Improvements in Label-Affixing Apparatus, of which the following is a specification.

This invention relates to improvements in apparatus for affixing labels and is particularly designed for applying labels to bread loaves.

The principal object of the invention is to provide a manually operated apparatus carrying the labels in a rolled strip and dispensing them singly in such manner as to adhere to the surface upon which they are applied.

This object is attained by the novel construction and combination of parts hereinabove described, and shown in the accompanying drawings, forming a material part of this disclosure, and in which:—

Figure 1 is a top plan view showing a label affixing implement made in accordance with the invention.

Fig. 2 is a side elevational view of the same, the side being broken away in order to disclose the construction.

Fig. 3 is a longitudinal sectional view taken on line 3—3 of Fig. 1.

Fig. 4 is a fragmentary view taken substantially on the same line, showing the front portion of the apparatus, the parts being in a different position.

Fig. 5 is a transverse sectional view taken on line 5—5 of Fig. 3.

Fig. 6 is a fragmentary transverse sectional view taken on line 6—6 of Fig. 3.

Fig. 7 is another side elevational view, similar to Fig. 2, showing the parts in a different position and indicating the manner of operation, and

Fig. 8 is another longitudinal sectional view similar to Fig. 3 but showing a modified form of construction.

Referring to the drawings, the numeral 15 indicates a square tubular handle open at the bottom, and provided with a curved lateral hand guard 16, engageable with the digit finger of the operator, while upon the other side is a similar curved guard 17, engageable by the thumb so as to guide the operator's hand in an obvious manner.

The forwardly extending portion of the handle 15 merges into side frames 18 and 19, both being extended below the level of the handle element 15, the upper wall 30 of which extends partially over the side plates, the outer plate 18 of which is turned to form an end 21 and then outwardly at 22, where it is secured to the inner plate 19 by screws or like fastenings, thus forming a rigid rectangular hollow frame.

Attached to the opposite side plate 19 is an angular element 23 formed with the thumb guard 17, and merging into a plate 24, disposed parallel with the plate 19, and then bent at a right angle inward, as at 25, where it is secured to the angular extension 26 of the plate 19.

A lever having a hub 28 is pivotally mounted upon the shank of a bolt 29, fixed in the side plates 18 and 19, the lever having extending ends, respectively 30 and 31, to the former of which is attached a strip 32, having an extending portion 33, terminating in an angular element 34, adapted to be received within the hollow handle 15 when the lever is drawn up by an operator, as best shown in Fig. 7.

The opposite end 31 of this lever is forked to receive the upturned angular end of link 35, pivotally engaged within the forks by a pin 36. The outer end of the link 35 is pivoted on the bolt 38 with the lower end of a lever 40, pivoted at its outer end on a bolt 41, the head of which passes through the inner side plate 19, its point extending through an opening formed in the outer plate 18 and fixed in a raised casing 42 extending laterally outward from the plate 18, with which it is firmly engaged.

The casing 42 extends downwardly alongside the plate 18 for a considerable distance, and acts as a keeper for the lower end 44 of a helically coiled spring 45, surrounding the body of the bolt, the opposite end 46 of the spring engaging with a bent clip 47, formed on the upper edge of the lever 40, the effect of the spring being to normally maintain the handle in the position shown in Fig. 2.

Rotatably engaged upon the body of the bolt 29 is the outer end of another lever 50, the same extending toward the front and pressed normally downward by the effect

of a coiled spring 82, carried on a screw, the end 53 of the spring engaging with a clip 54, extending from the lever arm.

Formed in the outer portion of the lever 50 is an elongated slot 55, through which freely passes the body of the bolt 38, by which the lever 50 is moved up or down when the actuating lever moves the bolt 38 within the slot.

10 A downwardly curved arm 56 is formed with the lever 50, the same terminating in a lifting toe 57, the purpose of which will be further on described.

15 A rolled strip of paper 60, upon which is printed the labels to be affixed, is loosely mounted upon a spindle 61, the spindle having a collar 62, adapted to make contact with the outer surface of the plate 24, its inner end being rotatably mounted in the plate 19 so that the roll is positioned within the space therebetween.

20 The extending end of the spindle 61 is held in engagement by a spring clip 63, mounted upon the pin 64, the clip having an extending portion 65, acting in the manner of a handle by which its slotted portion 66 may be raised, permitting the spindle to be withdrawn, thus providing means whereby the roll may be renewed or changed in an easy and expeditious manner.

30 The paper strip is directed downwardly passing under a guide pin 68, over the bottom plate 69, formed with the raised elements 70, attached to the plates 19 and 24 respectively, the extending end of the strip being held downward by inwardly extending channel shaped guides 71, having raised inner edges 72, turned up at their front ends 73, so that the paper may be easily guided therebelow, and presenting a space 75, between their inner adjacent edges.

40 As best illustrated in Figs. 1, 2, 3 and 7, the lever 50 carries intermediate its ends a transverse stud or pin 52 to the outer end of which the upper end of a narrow plate or strip 79 is secured by guiding the material of said strip around the pin. This plate 79 has intermediate its ends, an opening through which the end of a spring 81 is passed from below to engage and press against its upper face, while the other end of the spring is coiled around the pin 52 and is then secured at a certain distance from said pin to the lever 50. A paper feeding finger 80 is secured to the lower end of the plate 79 and presses with its free end against the outer strip which rests upon the plate 69. Upon the operation of lever 31, the lever 50 will be depressed taking along the pin 52 and plate 79 pressing with its finger upon the paper strip so that the same will be fed one step upon each operation of lever 31.

45 Another spring 85 is coiled about a bolt 86, engaging between the plates 19 and 24, one end 87 of the spring being secured in a

clip 88, formed with the plate 24, while the other end 89 extends toward the front of the implement and is received in a central recess 90, formed in a sliding head 91, fixed to a vertical plate 92, having teeth or serrations 93, at its lower extremity, and guided to operate vertically between guides 94 and 94', secured upon the inner sides of the walls 19 and 24, the toothed plate being adapted to shear the extending end of the paper strip 75 over the square outer edge of the bottom plate 69, the same registering with the plates 118, carried by their angular elements 119.

50 A pair of spring prongs or fingers 95, are secured to the front plate 25 extending into the space rearward therefrom, above the level of the bottom plate 69, and adapted to contact therewith are a pair of pins 96 rigidly engaged in the block 91, thereby cushioning the cutter head, when forced 85 downward by the spring 89.

55 An extending plate finger 98, is formed with a strip 99, rigidly secured to the front of the plate and which operates to press the label firmly upon the article to which it is applied, the finger moving with the cutter plate 92.

60 Projecting laterally from the block 91 is a block 100, having an angular upper surface 101, and a level lower surface, adapted to be forced upward by the lifting toe 57 of the lever 50, when the latter is raised.

65 The lower surface of the block 100 is also normally engaged by a detent 102, carried by a flat spring 103, fixed upon a block 104, attached to the rear side of the plate 21, and formed with the spring 103 is a curved upper guiding edge normally pressing against the angular face of the block.

70 Formed with the lever 40 is an extending arm 108 adapted, when a handle 33 is raised, to make contact with the inner side of the detent 102, pressing it toward the front and releasing the block 100, which is then forced down, due to the effect of the spring 85, 110 causing the paper strip to be severed, and forcing the same upon the surface of the article to be labeled.

75 In order to prevent a retrograde movement of the paper strip, when it has been advanced by the spring finger 80, a pair of spring fingers 110, are adapted to press the paper strip tightly downward upon the plate 69, immediately adjacent to the path of the knife 92, these spring fingers being formed with a thin spring plate 112, bent around a bolt 114, extending between the partition plates 19 and 24, the extending rear end 115 of the coiled plate being held by a rod 116, secured by the rivet 117, to one of the plates 70, the arrangement being such that the spring fingers 110 are forced downward at all times, while they are so positioned as to prevent the paper from moving rearward when it has once been advanced.

In operation, a roll of the paper having been entered in the space between the walls 19 and 24 upon the spindle 61, and the same having been engaged in operative position, 5 the extending end of the coiled strip is passed under the pin 68 and below the channel guides 71, sufficient for the fingers 80 to engage with the same. At that time the cutter plate 92, and attached parts are raised 10 and held in a raised position, due to the engagement of the block 100 with the spring 102.

Upon raising the handle from the position shown in Fig. 2, into that indicated in 15 Fig. 7, the lever end 31 will be depressed, causing the bolt 38 to move within the slot 55, which action rotates the lever 40 upon the axis 41, and ultimately causes the arm 108 to make contact with the detent 102, 20 forcing it outwardly against the spring 103, which if continued, will release the block 100, permitting it, together with the cutter, to descend under the impetus of the spring 85.

25 Simultaneously with rotating the slotted lever 50, the lifting toe 57 is depressed, which, due to its leverage, moves downward in advance and completely out of the path of the block 100, prior to its release, so that 30 when the detent 102 is disengaged from the block 100, the cutter head and knife carried thereby is impelled downward, until the pins 96 make contact with the spring arms 95, cushioning its descent, at which 35 time the label will have been severed and affixed to the goods.

Immediately upon release of pressure upon the actuating lever 33, the parts are returned to their normal initial position, due 40 to the effect of the spring 45, the lifting toe 57 making contact with the lower side of the extended block 100, raising it upward until the detent 102 has been engaged thereunder, whereupon the implement is 45 ready for a further operation.

From the foregoing it will be seen that an effective implement has been disclosed for attaching labels, which may be applied in an expeditious manner with a minimum 50 of physical energy in operation.

Having thus described my invention what I claim as new and desire to secure by Letters Patent, is:—

1. In a label affixing apparatus, the combination with a hollow sectional frame, and a handle extending therefrom adapted to carry a roll of paper rotatably mounted in said extension, means for guiding and feeding said paper, a knife having serrations at 55 its cutting end mounted in the path of the paper, said knife being spring impelled downward, a detent engageable with said knife whereby it is normally held in a raised position, an actuating lever pivoted 60 in said body, said lever being adapted for a

manual operation, a detent releasing lever, a link connecting said actuating lever and said detent releasing lever, a slotted lever pivoted in the outer end of said body, and a lifting toe formed with said slotted lever 70 whereby said knife is raised, and means carried by said knife for pressing the label firmly upon the article.

2. In a label affixing apparatus, the combination with a hollow body having a handle attached at one end and a hollow extension secured laterally on said body, adapted to carry a paper strip, means for advancing a definite length of the paper strip, a knife mounted to operate vertically in said extension, a spring adapted to force said knife downward, a block formed with said knife extending into the body, a detent engageable with said block whereby it is normally held in a raised position, means for 80 guiding said knife, a cushioning means adapted to engage with said knife near the lower limit of its travel, a hand operated lever pivoted to said body, means combined therewith adapted to raise said knife, so as 85 to be engaged by said detent, and means operated by said lever adapted to move said detent out of engagement with said block whereby said knife may descend.

3. In a label affixing apparatus, the combination with a hollow metallic body having an extending handle at one end, a hollow lateral extension combined with said body, adapted to carry a roll of paper, means for feeding the paper, means for preventing retrograde movement of the paper, a serrated knife adapted to sever the paper, spring actuated means for forcing said knife downward, a block engaged with said knife extending into said body, a spring actuated 95 detent engageable with said block whereby it is held when in a raised position, a manually operated hand lever pivoted in said body, a slotted lever pivoted in said body, means actuated by said hand lever whereby 100 the slotted lever is caused to rotate upon its axis, a link carried by said manually operated hand lever, a detent releasing lever connected to said link, a raising toe formed with said slotted lever adapted to raise said 105 knife after its descent, and a presser foot carried by said knife adapted to press the label firmly upon the article.

4. In a label affixing apparatus, the combination with a handled hollow body, a hollow extension secured laterally thereto adapted to carry a paper strip, means for removing said strip, a spring actuated finger adapted to advance said paper strip forward, other fingers adapted to prevent it 120 from moving rearward, a vertically operated cutter head in said extension, a cutter on said head, a detent engageable with said cutter whereby it normally is held in a raised position, a spring adapted to force 125 130

said cutter head normally downward, pins carried in said cutter head, spring elements adapted to contact with said pins whereby the downward movement of said head is cushioned at the rear of its stroke, a hand lever pivoted in said body, means combined therewith for releasing said detent, and

means for raising said lever so as to engage with said detent, said means becoming operative at one full movement of said hand lever.

In testimony whereof I have affixed my signature.

WINCENT KWASIS.
